UNITED STATES PATENT OFFICE.

HENRY HAGUE VAUGHAN, OF MONTREAL, QUEBEC, CANADA.

LAVATORY EQUIPMENT FOR PASSENGER-CARS.

1,122,444.

Specification of Letters Patent. Patented Dec. 29, 1914.

Application filed September 10, 1913. Serial No. 789,169.

To all whom it may concern:

Be it known that I, HENRY HAGUE VAUGHAN, of the city of Montreal, Province of Quebec, Dominion of Canada, have invented certain new and useful Improvements in Lavatory Equipments for Passenger-Cars; and I do hereby declare that the following is a full, clear, and exact description thereof.

10 My invention relates more particularly to the lavatories usually located in the smoking compartments of sleeping cars, and has for its object to increase the seating capacity of these compartments and at the same time give the maximum lavatory facilities.

The invention may be said briefly to consist of a combination seat and wash basin with water supply and waste connections.

15 The seat proper is tilttable from normal horizontal position to vertical position and the back is tilttable from normal vertical position to horizontal position and has mounted therein one or more wash-basins with water supply and waste connections the latter connecting with a drainage pan adapted not only to catch the discharged waste but any water remaining in the basins when the lavatory is converted into a seat.

20 For full comprehension, however, of my invention reference must be had to the accompanying drawings forming a part of this specification, in which similar reference characters indicate the same parts, and wherein:

25 Figure 1 is a plan view of one end of the smoking compartment arranged for sitting room; Fig. 2 is a transverse sectional view illustrating the convertible seat in elevation; Fig. 3 is a vertical sectional view 40 taken on line A A Fig. 2 with the seat converted into a lavatory; and Fig. 4 is a longitudinal vertical sectional view taken just inside the side of the car and illustrating the convertible seat in elevation and arranged 45 as a seat.

The seat proper is indicated at *b* and the back at *c*. A pair of fulcrum plates *d* provided with trunnions *e* are secured to the ends of the seat and fulcrum plates *f* having trunnions *g* secured to the ends of the back. These plates are so disposed that the seat and back may be tilted from the positions shown in Fig. 4 to the positions shown in Fig. 3. The trunnions are seated in sockets mounted on the interior of the car side *h* and a small partition or seat arm *i* sepa-

rating this seat from a fixed basin *j*. The trunnions *g* of the back are so placed that the center of gravity is thrown between them and the end partition of the compartment. This end is double and presents a wall section *k* the lower edge of which acts as a stop for the back *c* when turned down as in Fig. 3, and a part *m* having a lining *n* of sheet metal.

30 A pair of basins *2* and *3* are countersunk in the back *c* and each has a water supply pipe *4* with upturned open end *5* arranged to inclose a fixed water pipe *6* when the back is turned down and move from it when the seat is re-established. The pipe *4* is controlled by the usual push faucet *7*. Each basin has also a waste pipe *8* controlled by a push valve *9*, and these waste pipes have pieces of hose *10* connected thereto, while a drip-pan *12* of substantially the same length as the back of the seat is located beneath the same. The bottom of the pan is inclined from one to the other and its lower end has a waste-pipe *13* discharging 40 through the floor of the car.

35 The space between the walls *k* and *m* is sufficient for the pipe fittings into which access may be had through an opening *15* in partition *m*.

45 In order to afford standing room in front of the basins the seat *b* is made to tilt beneath the same as before mentioned, and for convenience a basket *16* for soiled towels is attached to the underside thereof and arranged to present its mouth upwardly, as shown in Fig. 3, when the seat is tilted.

50 Stability is imparted to the seat by placing the center of gravity between its fulcrum and front edge which rests on supports *20* and *21* secured to the arm *i* and car-side respectively.

55 Tumbler holders *25* are so placed that they are accommodated by the basins when the back is in normal position.

60 This construction and particular arrangement of parts increases the seating capacity of the smoking compartment without reducing the usual lavatory facilities and the change from one to the other may be readily 65 made by the porter or any other person owing to the simplicity of operation. Another advantage being that the lavatory is not exposed until required for use, thus protecting it from dust and other soiling influences.

65 70 75 80 85 90 95 100 105 110 115

Although I have described my invention

as an equipment of the smoking compartment of a passenger coach I am not confined to this use as it may be applied with advantage to other passenger compartments and to other carriers than railway coaches.

What I claim is as follows:—

1. In a passenger compartment, the combination with a displaceable seat member and a displaceable back member, of a lavatory equipment exposed when the back member is displaced.
2. In a passenger compartment, the combination with a displaceable seat member, of a lavatory equipment carried by the seat member and movable therewith and exposed when the seat member is displaced.
3. The combination with a tiltable seat and a tiltable back of a basin mounted within the back, and having water supply and waste connections.
4. The combination with a seat tiltable to vertical position, a back tiltable to horizontal position over the tilted seat, a basin mounted within the back and having water supply and waste pipes.
5. The combination with a seat tiltable to vertical position, a back tiltable to horizontal position over the tilted seat, a basin mounted within the back and having water supply and waste pipes, and an elongated drip pan beneath the back and with which the waste pipe communicates and arranged to receive the drips from the basin when the back is in normal position.

6. In a compartment containing a double partition containing a space and having an opening for access to the space, a seat tiltable to vertical position, a back tiltable to horizontal position over the tilted seat, a basin mounted within the back and having water supply and waste pipes, the back engaging a part and being partially supported by a part of the partition.

7. In a passenger compartment, the combination with a displaceable seat-back, of a basin carried by the back and hidden thereby when the seat is in use and movable therewith and exposed when the back is displaced, the said basin having means whereby it is drained when the seat-back is returned to position.

8. The combination with a seat tiltable to vertical position, a back tiltable to horizontal position over the tilted seat, a basin mounted within the back and having water supply and waste pipes, the fulcrums of the seat and back being offset from their centers of gravity thereof, and means for coating with the fulcrums in the support of the said seat.

In testimony whereof I have signed my name to this specification in the presence of two witnesses.

HENRY HAGUE VAUGHAN.
